To all whom it may concern:

Be it known that I, AUGUSTUS BROWN MORISON, of Jersey City, in the county of Hudson and State of New Jersey, have invented and produced a new and original Design for the Exterior of a House, of which the following is a specification, reference being had to the accompanying drawings, forming a part thereof.

15 Similar letters of reference designate corresponding parts in all the figures.

A house of this design consists of two stories with an attic third story within a gable roof, and a wing or L extension of two stories sur-
20 mounted by a gable roof, the front of the house having a veranda covered by a shed roof at the first story, one side of the house having a projecting portion in the first and second stories and surmounted by a gable roof branching from the main roof, and a second

veranda running along one side of the first floor of the wing or extension and having a hip roof, all as hereinafter more particularly described in detail with reference to the drawings.

30 A B C designate the exterior of the first and second stories and attic, which at one side are partly comprised in a projecting portion D, the whole being surmounted by a gable roof E F. The first story in the front has a ver- 35 randa G with a shed roof g. At the rear there is a wing or L extension H, two stories high and surmounted by a gable roof h, at the rear of which wing there is a further projecting portion I to the first story, having a hip roof i.
